UNITED STATES PATENT OFFICE

148,772

DESIGN FOR A HELICOPTER

Wesley J. Davis, Los Angeles, Calif.

Application August 5, 1946, Serial No. 132,284

Term of patent 7 years

(Cl. D71—1)

To all whom it may concern:

Be it known that I, Wesley J. Davis, a citizen of the United States, residing in the city of Los Angeles, county of Los Angeles, and State of California, have invented a new, original, and ornamental Design for a Helicopter, of which the following is a specification, reference being had to the accompanying drawings, forming part thereof, in which:

Fig. 1 is a top plan view of a helicopter showing my new design;

Fig. 2 is a front elevation of the helicopter;

Fig. 3 is a rear elevation of the device; and

Fig. 4 is a perspective view from in front and above, with the lifting rotor assembly broken away.

This application is a continuation in part of my co-pending application, Serial No. D. 117,001, filed December 19, 1944, for Helicopter, which is now abandoned.

I claim:

The ornamental design for a helicopter, as shown.

WESLEY J. DAVIS.
